(57) **CLAIM**

The ornamental design for a diagnostic probe, as shown and described.

DESCRIPTION

FIG. 1 is a perspective view of a diagnostic probe of my new design;

FIG. 2 is a second perspective view thereof;

FIG. 3 is a third perspective view thereof;

FIG. 4 is a fourth perspective view thereof;

FIG. 5 is a back view thereof;

FIG. 6 is a front view thereof;

FIG. 7 is a right view thereof;

FIG. 8 is a left view thereof;

FIG. 9 is a top view thereof; and,

FIG. 10 is a bottom view thereof.

The broken lines shown are included for the purpose of illustrating portions of the diagnostic probe that form no part of the claim.
